7 Claims. (Cl. 221—11)

ABSTRACT OF THE DISCLOSURE

A housing having a plurality of vertically overlying magazines mounted therein, each adapted to receive a plurality of cans therein, canted toward a vertical passageway positioned in communication with one end of each of said magazines. An elongated slot through either wall of said housing adjacent the one end of each of said magazines and a bar extending through pairs of said slots and fixedly engaged in a carriage mounted for generally vertical sliding movement relative to said housing. Said bars being in magazine blocking positions once the carriage is in a first position and in passageway blocking positions when the carriage is in a second position. Spring means biasing said carriage toward said second position and latch means attached to the housing so as to extend at least partially into the passageway. When the passageway has cans therein, the latch means is maintained in a position wherein the carriage is engaged and held in the first position, and when the cans are removed from the passageway, the latch means moves under spring bias into a position wherein the carriage is allowed to move to the second position. A star wheel mounted at the bottom of the passageway and rotated by a gear-motor arrangement which is activated by an operator. The star wheel removes one can at a time from the passageway. When the passageway is empty, the latch means allows the carriage to move to the second position which allows one can from each of the magazines to enter the passageway. The cans rest on the rods and urge the carriage toward the first position wherein the cans are free to leave the passage by means of the star wheel. The various magazines are loaded from the end opposite the passageway so that the first cans placed in the magazine are the first cans used.

Background of the invention

Field of the invention.—In the product dispensing field and especially in can dispensing apparatus, it is important that the cans be handled relatively gently and that the older cans be dispensed first. It is also important to provide apparatus with very few moving parts and which operates reliably.

Description of the prior art.—In the prior art devices for dispensing cans, a multiplicity of moving parts are utilized to dispense the cans, thereby, increasing the complexity of servicing the apparatus and decreasing the useful life and reliability. Also, in the prior art apparatus, reloading the can-receiving magazines is difficult and time consuming because they are not vended in a first-in, first-out manner. In general, to reload all of the prior art apparatus, the cans already contained therein must be removed and placed in the apparatus last to make sure that they are dispensed first.

Summary of the invention

The present invention pertains to an improved can dispensing apparatus and more particularly to can dispensing apparatus having very few moving parts and constructed so that the first cans placed in the machine are the first cans out.

2

It is an object of the present invention to provide new and improved can dispensing apparatus.

It is a further object of the present invention to provide can dispensing apparatus which dispenses the cans on a first-in, first-out basis.

It is a further object of the present invention to provide can dispensing apparatus which is highly reliable and simple to maintain.

These and other objects of this invention will become apparent to those skilled in the art upon consideration of the accompanying specification, claims, and drawings.

Brief description of the drawings

Referring to the drawings, wherein like characters indicate like parts throughout the figures:

FIGURE 1 is a front view of a vending machine having a plurality of the present apparatus therein, parts thereof removed;

FIGURE 2 is an enlarged view of a single vending apparatus as seen from the line 2—2 in FIGURE 1;

FIGURE 3 is a view of the apparatus as seen looking from left to right in FIGURE 2, parts thereof removed;

FIGURE 4 is a sectional view as seen from the line 4—4 in FIGURE 3;

FIGURE 5 is a view similar to FIGURE 4, parts thereof removed, with the various components in a different position;

FIGURE 6 is a view of the apparatus as seen from the line 6—6 in FIGURE 3, parts thereof removed, with the various components in the same relationship as illustrated in FIGURE 5;

FIGURE 7 is a view similar to FIGURE 5 with the various components in a different relationship;

FIGURE 8 is a view similar to FIGURE 6 with the various components in the same relationship as illustrated in FIGURE 7;

FIGURE 9 is an enlarged sectional view as seen from the line 9—9 in FIGURE 4;

FIGURE 10 is a sectional view as seen from the line 10—10 in FIGURE 2 on an enlarged scale;

FIGURE 11 is an elevational view on a slightly reduced scale as seen generally from the line 11—11 of FIGURE 10 showing the latch means in detail;

FIGURE 12 is a view of the latch means as seen from the line 12—12 in FIGURE 11; and

FIGURE 13 is a schematic illustration of the electrical components in the machine illustrated in FIGURE 1.

Brief description of the preferred embodiment

Referring to FIGURE 1, a vending machine generally designated 20, is illustrated having five separate vending modules, generally designated 21, therein. Each of the modules 21 operate separately and it should be understood that any number of modules 21 might be utilized in a machine. Also, in this embodiment, the individual modules 21 in the machine 20 are interchangeable and replaceable. In the FIGURES 2 through 12, a single module 21 is illustrated for simplicity and it should be understood that each of the other modules 21 are similar.

Referring to FIGURES 2 through 12, a module 21 is illustrated having a housing 22 with a box-like configuration. The housing 22 has a pair of parallel opposed side walls 23 and 24, a front 25, and a rear 26. The top and bottom of the module 21 have no operative function and do not enter into the description thereof. Also, it should be noted that the front 25 and rear 26 refer to the position of the module 21 in the machine 20, and are used for expedience in the description rather than as a limiting term. The module 21 is constructed to vend cans of the size illustrated in the various drawings and the width between the side walls 23 and 24 is approximately equal

to the length of these cans. Also, many of the remaining parts are constructed and will be described relative to the diameter of these cans. It should be understood, however, that modules 21 and machines 20 can be constructed, as will be described, so that cans having substantially any desired size and shape can be vended.

A plurality of magazines 30 are formed within the housing 22 in vertically overlying relationship by cutting the side walls 23 and 24 and bending portions thereof inwardly to form ledges therealong. A single magazine 30 is formed by a pair of ledges, one on side wall 23 and a mating ledge on side wall 24, lying in substantially the same plane and slanting downwardly from the front 25 toward the rear 26. In this embodiment there are ten magazines 30 all of them being approximately parallel and lying slightly more than the diameter of a can apart. Each of the magazines 30 extends from approximately the front 25 to a distance somewhat greater than a can diameter from the rear 26. A vertical passageway 31 is formed between the ends of the magazines 30 and the rear 26 of the housing 22. The front 25 of the housing 22 is open, and cans are placed in the magazines 30 therethrough. Because of the slant of each of the magazines 30, the cans are urged downwardly toward the passageway 31 by the force of gravity. It should be understood that other methods could be utilized to force the cans from the magazines 30 into the passageway 31, but the apparatus shown is the preferred embodiment and is utilized because of its simplicity.

The housing 22 has a plurality of elongated slots 35 in each of the side walls 23 and 24 adjacent the lowermost end of each of the magazines 30. Each of the slots 35 in the side wall 23 has a mating slot in the side wall 24 which is approximately parallel and coextensive therewith. Each pair of slots 35 in the side walls 23 and 24 extend from a position approximately the radius of a can above the ledges forming a magazine 30 and adjacent the lower end thereof to a position approximately in a line with the ledges forming the magazine 30 thereabove, but spaced therefrom into the passageway 31. The distance 40 between the upper end of the slot 35 and the rear 26 of the housing 22 is somewhat less than the diameter of a can, while the lower end of the slots 35 and the lower ends of each of the magazines 30 lies approximately in a plane.

A carriage 36 has a rear portion 37 and two side portions 38 extending outwardly therefrom to provide a generally U-shaped cross section. The carriage 36 is positioned so that the rear portion 37 thereof overlies the rear 26 of the housing 22 and the side portions 38 extend slightly farther than the slots 35. A plurality of rods 40 are fixedly engaged in the side portions 38 of the carriage 36 so that one extends through each pair of slots 35. A tension spring 41 is attached between the rear 26 of the housing 22 and the rear portion 37 of the carriage 36 so as to bias the carriage toward a position in which the rods 40 are located at the upper ends of the slots 35.

Latch means, generally designated 45, includes an elongated portion 46 pivotally mounted at the upper end thereof on the rear 26 of the housing 22 between the rear 26 and the carriage 36. The lower end of the elongated portion 46 has a protuberance 47 positioned thereon so as to project into the passageway 31 through an opening 48 in the rear 26 of the housing 22 when the elongated portion 46 is hanging vertically downward. Referring to FIGURES 11 and 12, the latch means 45 can be seen in detail. A torsion spring 49 is affixed in the usual manner between the pivotal mounting means and the elongated portion 46 to produce a bias on the latch means 45 urging the protuberance 47 toward the opening 48. The side of the elongated portion 46 opposite the protuberance 47 and adjacent the carriage 36 has an outwardly projecting step 50 attached thereto. The step 50 is comprised of a member 51 having a generally U-shaped cross section, positioned in overlying relationship to the elongated por-

tion 46, a pin 52 pivotally attaching the member 51 at the upper end thereof to the elongated portion 46, a pin 53 fixedly attached to the elongated portion 46 and slidably engaged in a slot in the member 51 to limit the pivotal movement thereof and a spring 54 urging the member 51 outwardly away from the elongated portion 46. The step 50 is positioned to engage an opening 55 in the rear portion 37 of the carriage 36 adjacent the lower end thereof and maintain the carriage 36 in a lower position wherein the rods 40 are in the lower-most end of the slot 35. The step 50 is constructed so that the carriage 36 is free to move upwardly when the elongated portion 46 is hanging vertically downwardly and the protuberance 47 at the lower end thereof extends into the passageway 31 through the opening 48. The opening 55 is engaged by the step 50, thereby preventing upward movement when cans in the passageway 31 force the protuberance 47 outwardly through the opening 48.

A star wheel 60 is rotatably mounted at the lower end 20 of the passageway 31 to remove one can at a time therefrom and direct it into an outlet passageway 61. The star wheel 60 is mounted between the side walls 23 and 24 in the lower end of the vertical passageway 31 by an axle journaled in the side walls 23 and 24. A gear 62 is mounted exteriorly of the side wall 23 on the outer end 25 of the axle. The gear 62 is engaged with an idler gear 63 which is driven by a drive gear 64. The drive gear 64 is driven by a motor through an internal gear box 66. When the motor 65 is energized through the circuitry, 30 which will be described in conjunction with FIGURE 13, the star wheel 60 turns 90 degrees and the drive gear 64 makes a complete revolution.

One end of an elongated arm 70 is concentrically attached to a wheel 71 which is fixedly attached coaxially to the drive gear 64 for rotation therewith. As the wheel 71 rotates, the rotational movement is transferred to linear movement at the opposite end of the elongated arm 70. An elongated slot 72 is formed in the arm 70 adjacent the opposite end thereof and extends along the longitudinal axis thereof. A pin 73, which is fixedly attached to the outer surface of the side portion 38 of the carriage 36, is engaged in the slot 72 for sliding movements therein. The pin 73 extends outwardly through the slot 72 a substantial distance so that a hook 74 pivotally attached adjacent the end of the elongated arm 70, can engage the pin 73, under circumstances which will be explained presently, and prevent movement thereof relative to the elongated arm 70. The hook 74 has an arm 75 attached thereto and extending outwardly approximately perpendicular thereto through a slot in a member 76 fixedly attached to the side wall 23 of the housing 22. The arm 75 converts the linear motion present at the end of the elongated arm 70 to rotational motion of the hook 74. The length of the slot 72 and the position of the pin 73 is such that when the carriage 36 is in its lower-most position, rotation of the wheel 71, and consequent rotation of the hook 74, does not cause the hook 74 to engage the pin 73. However, when the carriage 36 is near its uppermost position, rotation of the wheel 71 causes the hook 74 to engage the pin 73 and raise the carriage 36 to its uppermost position. Since the wheel 71 and the elongated arms 70 stop in the position illustrated in FIGURE 8, the carriage 36 is maintained in its uppermost position at least until the next rotation of the wheel 71.

Referring to FIGURE 13, an accumulator 80 is illustrated in block form, which accumulator is adapted to supply a suitable voltage, such as 115 volts 60 cycles between a pair of lines 81 and 82, and, upon the reception of a prescribed quantity of coins, complete a circuit between a line 83 and the line 81. The line 81 is connected directly to one side of each of the motors contained in each of the modules 21. In FIGURE 13, only the circuitry for two modules 21 is illustrated and it should be understood that any number of circuits can be connected thereto in a manner similar to the connection of motor 65 and

its associated circuitry, which will be explained presently. Motor 65 has associated therewith a double-pole, double-throw switch 84, a selector button 85, an electromagnetic coil 86, and a pair of latching levers 87 and 88. The lead 82 is connected to one movable contact 90 of the switch 84 having a pair of stationary contacts 91 and 92 associated therewith. The stationary contact 92 is connected directly to the other movable contact 93 which has associated therewith a pair of stationary contacts 94 and 95. The stationary contact 91 and the stationary contact 94 are connected directly together and to a movable contact 90a of the next double-pole, double-throw switch 84a. The stationary contact 95 is connected to the opposite side of the motor 65. The lead 83 is connected to one side of the selector button 85, while the other side is connected to one side of the electromagnetic coil 86. The other side of the coil 86 is connected through the normally closed contacts of a single-pole double-throw switch 99, to the lead 81. The lever 87 is generally L-shaped and pivotally mounted at approximately the center of the shorter arm. The movable contacts 90 and 93 of the switch 84 are connected to the lever 87 so that they are normally in engagement with the stationary contacts 91 and 94 respectively, but counter-clockwise rotation of the lever 87 brings them into engagement with the contacts 92 and 95 respectively. The lever 88 is a generally elongated member pivoted at one end and having a portion extending outwardly to form a hook adjacent the other end. A spring 96 is attached between the junction of the two arms of the lever 87 below the pivot point and approximately the center of the lever 88 and provides a counter-clockwise bias on the lever 87. However, the member 88 is normally hooked over the upper end of the short arm of the lever 87 to prevent rotation thereof. When the coil 86 is energized, the core thereof forms an electromagnet which attracts the lever 88 causing clockwise rotation thereof and unlatching the lever 87. Clockwise rotation of the lever 88 increases the bias of the spring 96 while unlatching the lever 87, which causes counter-clockwise rotation of the lever 87. The wheel 71 has a cam 97 attached thereto which engages the lower end of the long arm of the lever 87 to move the levers 87 and, consequently, 88 back into the latched position after a complete rotation thereof.

In the operation thereof, when a proper amount of coins are inserted in the accumulator 80 and the selector button 85 is closed, the electromagnetic coil 86 is energized unlatching the levers 87 and 88 if cans are in the passageway 31. Movement of the lever 87 in the counter-clockwise direction causes the movable contacts 90 and 93 to engage the stationary contacts 92 and 95, thereby, completing a circuit through the motor 65. The motor 65 then rotates causing the wheel 71 to make a complete rotation and the star wheel 60 to move 90 degrees. When the star wheel 60 moves 90 degrees, a can is removed from the passageway 31 and dispensed into the outlet passageway 61. When the wheel 71 has made a complete revolution, the cam 97 engages lever 87, returning the movable contacts 90 and 93 into engagement with the stationary contacts 91 and 94 and relatching the levers 87 and 88. The motor 65 is, thus, deenergized and no further movement occurs until the accumulator 80 again receives the proper amount of coins.

In the operation of the mechanism in the single module 21, the magazines 30 are filled from the front of the machine 20, or the upper end of each magazine 30, and the cans are retained in the magazines 30 by the rods 40. When the passageway 31 is empty, see FIGURE 5, the latch means 45 is disengaged from the opening 55 in the carriage 36, and the carriage 36 moves upwardly under the bias of the spring 41 at the speed of the movement of arm 70. As the carriage 36 and arm 70 move upwardly, the hook 74 engages the pin 73 (it should be noted that latch means 45 will move immediately upon the removal of the last can from the passageway 31 and the wheel 71 and arms 70 will be returning to their stationary 75

position as the carriage 36 moves upwardly), and maintains the carriage 36 in its upper position, the rods 40 are at the upper end of the slots 35 and cans are free to roll out of the magazines 30 into the passageway 31. However, because the rods 40 are situated less than a can's diameter from the opposite side of the passageway 31, cans (except for cans in the lower magazine) do not move down in the passageway 31 but simply rest on the rods 40. Cans in the lower magazine 30 move directly into the passageway 31 striking the latch means 45 and reactivating the switch 99 as will be apparent presently.

During the above-described movement, a can is situated in the star wheel 60, as illustrated in FIGURE 5, and activation of the motor 65 to dispense this can rotates the wheel 71 and lowers the arm 70 and hook 74. As the hook 74 is lowered, the carriage 36 moves downwardly under the weight of the cans resting on the rods 40 until the pin 73 is disengaged from the hook 74, and the rods 40 rest in the lower ends of the slots 35. Movement of the rods 40 in the slots 35 lowers the cans gently in the passageway 31 from the position illustrated in FIGURE 7 to the position illustrated in FIGURE 4. As the cans move into the position illustrated in FIGURE 4, the latch means 45 again engages the carriage 36 and prevents upward movement thereof.

The limit switch 99 is attached to the rear 26 of the housing 22 so that the elongated portion 46 of the latch means 45 depresses the button thereof and engages the pole or movable contact with the other stationary contact of the switch 99 when the passageway 31 is empty. The other stationary contact of the switch 99 is connected to the lead 82 through an indicator light 98, which indicates when energized that the module 21 associated therewith is empty. When the latch means 45 is in the position illustrated in FIGURE 4, the switch 99 is disengaged and in the normal position. Thus, when all of the magazines 30 and the passageway 31 are empty, the latch means 45 remains in the position illustrated in FIGURE 5 and the switch 99 is engaged, opening the circuit to the coil 86. It should be noted that the module 21 is designed so that at this time a can remains in the star wheel 60. Thus, for machines such as pop vending machines, which require cold cans, there is always a can left in the module 21. This can will be the first can vended after the module 21 is refilled, and, if cooling is required, will be cool so that no time lag is required before the machine 20 can be used. It should be understood that the star wheel 60 might be situated at the other end of the passageway 61 so that more than one can remains in the module 21 after the switch 99 is engaged, if it is desired. The operation of the module 21 will remain substantially the same but the passageway 61 will retain or store cold cans.

While I have shown and described a specific embodiment of this invention, further modifications and improvements will occur to those skilled in the art. I desire it to be understood therefore, that this invention is not limited to the particular form shown and I intend in the appended claims to cover all modifications which do not depart from the spirit and scope of this invention.

I claim:

1. Can dispensing apparatus comprising:
  - (a) a housing having a plurality of can receiving magazines mounted therein, said housing defining a passageway in communication with one end of each of said magazines for receiving cans from each of said magazines therein;
  - (b) carriage means attached to said housing for movement between a first and a second position;
  - (c) means biasing said carriage means toward said first position;
  - (d) gate means positioned adjacent said one end of each of said magazines and operatively connected to said carriage means for movement into a magazine closing position when said carriage means is in said second position and into a second position when said carriage means is in said first position;

- (e) latch means including a portion mounted for movement between a first position, in which said carriage means is engaged thereby and maintained in the second position, and a second position, said portion of said latch means being maintained in said first position by cans positioned in said passageway and moving into said second position upon the removal of a prescribed number of cans from said passageway;
- (f) said latch means further including means for biasing said portion of said latch means toward said second position; and
- (g) means operative to remove a can from said passageway and dispense the same upon the activation thereof.

2. Can dispensing apparatus as set forth in claim 1 wherein said magazines are disposed in vertically overlying relationship and said passageway is disposed approximately vertically at one end thereof.

3. Can dispensing apparatus as set forth in claim 1 wherein said gate means move into a passageway closing position in the second position for preventing movement of cans through said passageway.

4. Can dispensing apparatus as set forth in claim 3 having in addition second latching means connected to said can removing means and adapted to latch said carriage means in the first position after the movement of said carriage means into the first position upon the removal of the prescribed number of cans from said passageway, said second latching means unlatching said carriage means in response to the activation of said can removing means and allowing said carriage means to move to the second position.

5. Can dispensing apparatus as set forth in claim 4 wherein said gate means in the passageway closing position, are disposed in said passageway in a manner to receive cans from said magazines thereon and urge said carriage means toward the second position by the weight thereof.

6. Can dispensing apparatus as set forth in claim 2 wherein said magazines are mounted at an angle to the horizontal such that cans are urged toward said passageway under the influence of gravity and the end of each magazine opposite said one end is open for replenishing the supply of cans therein.

7. Can dispensing apparatus comprising:

- (a) a generally box-shaped housing having a plurality

- of can receiving magazines mounted in vertically overlying relationship, said housing defining a generally vertical passageway in communication with one end of each of said magazines for receiving cans from each of said magazines therein;
- (b) said housing having elongated slots through the walls thereof at either side of and adjacent said one end of each of said magazines, said slots extending away from said one end generally toward the center of said passageway;
- (c) carriage means having a generally U-shaped cross section disposed in slidably engagement over said housing so that the portions forming the arms of the U overlie said slots through said housing;
- (d) a plurality of rods fixedly positioned in said overlying portions of said carriage means, said rods extending through said slots in said housing so as to each be in a magazine blocking position at one end of said slots and in a passageway blocking position at the other end of said slots;
- (e) spring means urging said carriage means toward a position in which all of said rods are at said other end of said slots;
- (f) latch means including a pivotally mounted downwardly extending lever having a first position in which said latch means engages said carriage means and maintains it so that said rods are all at said one end of said slots and a second position in which it extends outwardly into said passageway;
- (g) spring means biasing said latch means toward said second position, said latch means being maintained in said first position by cans positioned in said passageway; and
- (h) means operative to remove a can from said passageway and dispense the same upon the activation thereof.
